United States Patent

Des. 239,522

Patented Apr. 13, 1976

239,522

GENERAL AVIATION AIRCRAFT

Ronald B. Wheatley, 1280 21st St. NW.,
Washington, D.C. 20036

Filed June 20, 1975, Ser. No. 588,830

Term of patent 14 years

Int. Cl. D12—07

U.S. Cl. D12—76

FIG. 4

FIG. 5

FIG. 1 is a perspective view of a general aviation aircraft in accordance with the invention;

FIG. 2 is a front elevation of the aircraft of FIG. 1;

FIG. 3 is a top plan view of the aircraft of FIGS. 1 and 2;

FIG. 4 is a left side elevational view of the aircraft of FIGS. 1-3; and

FIG. 5 is a bottom plan view of the aircraft of FIGS. 1-4.

I claim:

The ornamental design for a general aviation aircraft, as shown.
